(57) **CLAIM**

I claim the ornamental design for a citrus reamer device, as shown and described.

DESCRIPTION

FIG. 1 is an upper perspective view of a citrus reamer device showing my new design;

FIG. 2 is a left side view thereof, a right side view is a mirror image of the left side view; and,

FIG. 3 is a top view thereof.

The broken lines shown in the drawings illustrate portions of the citrus reamer device and form no part of the claimed design.
